(57) **CLAIM**

The ornamental design for a cellulite reduction massager, as shown and described.

DESCRIPTION

FIG. 1 is a top-front-left perspective view of a cellulite reduction massager showing my new design;

FIG. 2 is a bottom-rear-right perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right elevational view thereof; and,

FIG. 8 is a left elevational view thereof.

The broken lines showing a user interface in FIGS. 1, 3, 5, 7, and 8, the broken lines showing a light emitter in FIGS. 2 and 6, and the broken lines showing a power port in FIGS. 2, 4, and 6-8, are included for the purpose of illustrating environmental structure and form no part of the claimed design.
